[57] CLAIM

The ornamental design for a battery recharger, as shown and described.

DESCRIPTION

FIG. 1 is a front, top and side perspective view of the battery recharger embodying the design of the present invention;

FIG. 2 is a front elevational view thereof, the rear being a mirror image of the front shown in FIG. 2;

FIG. 3 is an end elevational view thereof;

FIG. 4 is an end elevational view thereof;

FIG. 5 is a top plan view thereof; and,

FIG. 6 is a bottom plan view thereof.

The broken line showing in FIG. 1 is included for the purpose of illustrating environmental elements only and forms no part of the claimed design.

FIG. 1

FIG. 2

FIG. 3

FIG. 4

FIG. 5

FIG. 6
